[57] CLAIM

The ornamental design for a urinal drip plate, as shown.

DESCRIPTION

FIG. 1 is a top perspective view of a urinal drip plate, showing my new design;

FIG. 2 is a bottom perspective view, with the locking plate attached;

FIG. 3 is a bottom plan view thereof;

FIG. 4 is a top perspective view of the locking plate portion of the claimed design; and,

FIG. 5 is a perspective view of the urinal drip plate, in use condition.

The broken line showing is for illustrative purposes only and forms no part of the claimed design.
